UNITED STATES PATENT OFFICE.

SIMEON SHERMAN, OF WESTON, MISSOURI.

IMPROVEMENT IN ROTARY ENGINES.

Specification forming part of Letters Patent No. **58,900**, dated October 16, 1866.

To all whom it may concern:

Be it known that I, SIMEON SHERMAN, of Weston, in the county of Platt and State of Missouri, have invented a new and Improved Rotary Engine; and I do hereby declare the following to be a full, clear, and exact description of the same, sufficient to enable any one skilled in the art to which the invention appertains to make use of it, reference being had to the accompanying drawings, in which—

Figure 1 is a central vertical longitudinal section on the line *x x*, Fig. 2. Fig. 2 is an elevation on the line *b b*, Fig. 1. Fig. 3 is a vertical section on the line *c c*, Fig. 1. Fig. 4 is a section on the line *a a*, Fig. 1. Fig. 5 is a section on the line *d d*, Fig. 1.

The improvement consists in the mode of operating the abutment valve-piece, which controls the steam-passages and closes that portion of the chamber after the piston has passed that point.

It also consists in the arrangement of the condenser in direct connection with the exhaust-openings, which are guarded by the rotating abutment-valve.

It also consists in the arrangement of the engine-pumps and condenser.

In the drawings, *A A* are standards supporting the main shaft, *B*, carrying the piston *C*, which has an expandible packing arrangement, *D E F*. The piston revolves in a chamber inside the casing *G*, the latter being supported by the walls of the condensing-chamber *H*, and ultimately by the floor *I*.

The segment of a cylinder, *J*, mounted on a shaft, *K*, and having bearings in the casing *G*, is perforated for the passage of steam to the chamber, and acts both as a valve and an abutment.

L is the inlet-port for the passage of steam from the boiler, and *M* are the passages in the valve *J*, by which steam is admitted to either side by the piston *C*, as it may be required to run the engine in either direction.

The exhaust-passages *M M*, on either side of the abutment-piece *J*, connect the steam-space in the cylinder with the condensing-chamber *N*, which has a perforated diaphragm, *O*, and a bottom, *P*, the latter opening automatically

under an accumulation of water above it, and being restored to position by the spring *Q*.

The water for the condensation of the steam in the chamber *N* is introduced into the latter by the pipe *R*, which proceeds from the chamber *S*, in which the chambered disk *T* rotates. This disk forms the cold-water pump, and acts as a chambered valve. The water flows in at the opening *U*, and a quantity equal to the aggregate capacity of the chambered recesses in the disk is carried forward at each revolution and permitted to flow through the pipe *R* to the condenser *N*.

The piece *J* acts as a valve for the admission and emission of steam to and from the cylinder, as well as acting as an abutment to close the annular steam-space at the proper times. It has a reciprocating rotary motion produced by the alternate action of the projection *V* and the spring *W* upon the cam *X*, which is attached to the shaft *K* of the valve *J*.

The projection *V* is upon the wheel *Y*, which latter is attached to and revolves with the main shaft *B*, and as the position of the projection agrees in position with the piston, the former, coming in contact with the cam *X*, rotates it, so as to remove the abutment and allow the piston to pass, as shown in Fig. 2.

As soon as the piston has passed, and the projection *V* has passed the cam *X*, the spring *W* on the cam restores the abutment to its position with one edge in contact with the periphery of the revolving cylinder from which the piston projects.

The packing arrangement in the piston consists of the portions *D E F*, the center piece of which comes in contact with the inner periphery of the steam-cylinder, the end pieces moving against the ends of the cylinder, expanded and kept in contact therewith by the spring *Z*.

The corners *g* or *h* of the abutment will close the annular steam-chamber at its lower portion at all times when the piston is not passing the abutment, as shown in Fig. 2.

If the piston be running, as shown in the figures, as indicated by the red lines on the figures, the edge *h*, Fig. 2, will bear against the surface of the internal cylinder, *C*, and the steam will pass in by way of the pipe *L*.

and through the port M' of the valve J , (see red arrows in Fig. 3,) while the escape-steam passes from before the piston out of the annular steam-chamber, by way of the port M , into the condenser N . (See Fig. 4.)

To reverse the engine the spring W is withdrawn from the notch t , in which it is placed, (see Fig. 1,) and is placed in the notch s , which has the effect of bearing or straining the valve J in the other direction, so that when freed from the contact of the piston the edge g , Fig. 2, of the abutment will close the steam-space, the steam be admitted through the port M , and be exhausted through the port M' .

The machine will be found valuable for many purposes by direct attachment of the saw, as shown in Fig. 1, or the shaft of a rotary pump, roller, paddle, driving-wheel, or other mechanical device.

It will be seen that the effect of the steam upon the piston may be stopped by placing the spring in the notch p , when the steam is shut

off from entrance into the cylinder by inlets M or M' , as is clearly shown in Fig. 3.

The reversal of the steam in this engine brings it to bear upon a different side of the piston and is absolute, not depending upon the stoppage of the piston before the crank reaches its dead-point, as in reciprocating engines generally, and in some rotary engines.

Having described my invention, what I claim therein as new, and desire to secure by Letters Patent, is—

1. The arrangement of the condenser in direct connection with the two exhaust-ports, guarded by a reciprocating rotary abutment-valve.

2. The described arrangement of the rotary engine, condenser, and chambered valve T , operating as described.

SIMEON SHERMAN.
